UNITED STATES PATENT OFFICE.

CHARLES E. BRADLEY, OF MONTCLAIR, NEW JERSEY, AND JOSEPH G. COFFIN, OF HEMPSTEAD, NEW YORK, ASSIGNEES TO GENERAL RUBBER COMPANY, A CORPORATION OF NEW JERSEY.

APPARATUS FOR SUPPLYING A DRYING MEDIUM.

Original application filed December 7, 1921, Serial No. 520,505. Divided and this application filed April 3, 1922. Serial No. 549,360.

To all whom it may concern:

Be it known that we, CHARLES E. BRADLEY and JOSEPH G. COFFIN, both citizens of the United States, and residing at Montclair, in the county of Essex and State of New Jersey, and Hempstead, Long Island, in the county of Nassau and State of New York, respectively, have invented a certain new and useful Apparatus for Supplying a Drying Medium, of which the following is a full, clear, and exact description.

This invention relates to an apparatus for supplying a drying medium, more particularly to means for supplying a suitable drying medium to a latex drying apparatus, such as that disclosed in our copending application, Serial No. 520,505, filed December 7, 1921, since become Patent No. 1,428,526, granted September 12, 1922, of which this application is a division.

Apparatus for supplying a heated drying medium may be divided broadly into two classes. First, those in which the drying medium is indirectly heated by transferring heat through an intervening wall from a heating element or medium. Second, those in which the drying medium is directly heated by mixing it with combustion products, or in which heated combustion products alone are used as the drying medium. Apparatus of the first type is not economical in that where it is desired to heat the drying medium to a relatively high temperature it is impossible to prevent large heat losses, as in practice all of the heat cannot be transferred from the heating medium to the drying medium. In addition, in certain cases it is desirable to add the combustion products used for the heating to the drying medium by reason of the improved effect obtained upon the material dried, as in our copending application above mentioned. Apparatus of the second type is also not economical, because as ordinarily constructed there is also a considerable loss of heat in these. In devices of the second type combustion is usually carried on at the ordinary furnace pressures, thereby allowing a considerable escape of heat through the usual furnace openings.

An object of our invention is to provide an improved means for supplying a heated drying medium.

Another object is to provide a means for supplying a heated drying medium in which heat losses are substantially eliminated.

Still another object is to provide an improved means for directly heating air or other gas by admixture of combustion products therewith.

A further object is to provide means, operating under reduced pressure, for supplying a regulable mixture of heated air and combustion products.

For a detailed disclosure of the invention reference is had to the accompanying specification and drawing, in which latter:

Fig. 1 is a horizontal section through the apparatus;

Fig. 2 is a vertical longitudinal section through the furnace proper, or combustion chamber.

Referring to the drawings, the furnace 1 comprises a combustion chamber 2, which is preferably elongated, and provided at one end with an oil burner 3 of any suitable type to which are connected the respective oil and air supply pipes 4 and 5. Any suitable means 6 for admitting air for combustion around the burner may be used. At the bottom the furnace is equipped with a suitable damper 7 for admitting additional air for combustion, which air passes inwardly through longitudinal passages 8 formed by the loosely placed fire brick 9, and is discharged upwardly into the combustion chamber through the transverse openings 10 formed by the fire brick 11. Adjacent the opposite end of the combustion chamber is an exhaust passage 12 which communicates with a mixing chamber 13 at an intermediate point in the latter, preferably at about its middle portion.

The mixing chamber in the present instance is formed as a straight relatively extended passage, and a screen 14 is removably disposed therein across the inlet of the exhaust passage 12 to the chamber, which screen is supported in position by the frame 15. This screen may be made of nichrome metal or any other suitable heat resistant material. At one end of the mixing chamber is an air inlet governed by the gate 16, while at the other end is an exhaust opening controlled by the gate 17, which opening is in connection with the casing 18 of a

suction fan. This fan may be driven in any desired manner, as by the belt 19. Leading from the fan casing 18 is a conduit 20 for conducting the mixed air and combustion products to the drying apparatus.

In operation the gate 17 is first closed, the gate 16 opened, and the oil burner 3 then started. This allows the combustion products to exhaust directly into the open air until such time as the furnace has been properly heated up. The gate 17 is then opened and the fan started, thereby causing an inflow of air to the mixing chamber through the aid inlet, and at the same time 10 exhausting the combustion products from the furnace proper through the passage 12, causing the combustion in the chamber 2 to take place under reduced pressure. The inflowing air and combustion products mix 15 in the mixing chamber 13 and are further mixed in passing through the suction fan. By a proper regulation of the burner 3, the various air inlets to the combustion chamber and the gate 16 any desired admixture 20 of combustion products and air may be obtained, and the temperature of the mixture properly regulated. The purpose of the screen 14 is to remove any solid particles 25 in the combustion products as they pass into the mixing chamber, particularly particles which may be drawn into the furnace through the various air inlets by reason of the suction. It will be noted that the screen is so disposed that after the air begins to 30 flow in through the gate 16 such air assists in cooling the screen and thereby lengthens its life. Moreover, by reason of its disposition it may be readily removed for repair or inspection. The fire brick pieces 35 9 and 11 are preferably loosely arranged in the furnace so that their disposition may be altered, as desired. It will be seen that 40 during the operation of the device combustion takes place in the chamber 2 under reduced pressure, and since air is being drawn in at all the inlets there are no heat losses whatever at such inlets, and the furnace operates at a maximum efficiency. Hence small cracks or leaks which would 45 ordinarily be objectionable do not in any way impair the operation of the furnace. By disposing the mixing chamber 13 at substantially a right angle to the exhaust passage 12 the combustion products are 50 given a sharp bend as they enter the mixing chamber and more quickly mixed with the air. This also eliminates the destructive action of radiant heat from the combustion chamber on the fan in casing 18. Moreover, 55 for the particular purpose for which the apparatus is designed, namely to furnish a heated medium for drying rubber latex, the use of combustion products in the drying medium is in some cases desirable. It 60 also lessens the percentage of free oxygen 65

in the drying medium, and thereby lessens the oxidizing effect of such medium on the rubber during the drying process. While it is evident that liquid, gaseous, or even solid fuel may be utilized in the furnace 70 proper, it is preferable to use liquid or gaseous fuel, owing to the absence under proper working conditions of any solid combustion products which it would be difficult to eliminate from the drying medium. As 75 it is desired that there shall be complete combustion in the combustion chamber, it should be made of a length sufficient to obtain this result.

While a specific embodiment of the invention has been disclosed, it is obvious that changes may be made therein and it is not desired to limit the invention otherwise than as set forth in the appended 80 claims.

Having thus described our invention, what we claim and desire to protect by Letters Patent is:

1. An apparatus for supplying a drying medium comprising a combustion chamber, 90 a mixing chamber, a passage leading from adjacent the end of the combustion chamber to an intermediate point of the mixing chamber, an air inlet at one end of the mixing chamber, and means at the other end thereof for exhausting mixed air and combustion products.

2. An apparatus for supplying a drying medium comprising a combustion chamber, regulable means for supplying air thereto, 100 a mixing chamber, a connection from said combustion chamber to an intermediate point of said mixing chamber, an air inlet at one end of the mixing chamber, an outlet at the other end, controlling means for 105 said inlet and outlet, and a suction device connected to said outlet.

3. An apparatus for supplying a drying medium comprising a combustion chamber, means at one end thereof for admitting 110 fluid fuel, regulable means for admitting air, an outlet adjacent the other end of the chamber, a mixing chamber connected thereto, a regulable air inlet to said mixing chamber at one end, an outlet at the other end, 115 and a suction device at said outlet.

4. An apparatus for supplying a drying medium comprising a combustion chamber, means at one end thereof for admitting fluid fuel, regulable means for admitting air thereto, an outlet at the other end, a mixing chamber connected at an intermediate point to said outlet, an air inlet at one end of said mixing chamber, a regulable outlet at the other end thereof, and 125 suction means for conducting away the mixed air and combustion products.

5. An apparatus for supplying a drying medium comprising a combustion chamber, regulable means at one end thereof for 130

burning fluid fuel, a mixing chamber, a passage leading from the opposite end of said combustion chamber to an intermediate point of said mixing chamber, a screen disposed in said mixing chamber at the inlet of said passage thereto, an air inlet at one end of the mixing chamber, an outlet at the other end thereof, and suction means at said outlet for exhausting and conducting away the mixed combustion products and air.

6. An apparatus for supplying a drying medium comprising an extended combustion chamber, an extended mixing chamber, an exhaust passage leading from the combustion chamber to the mixing chamber, oppositely disposed openings in the mixing chamber, controlling means for said openings, a discharge passage connected to one 15 of said openings, and a suction device disposed in said passage.

7. An apparatus for supplying a drying medium comprising an extended combustion chamber, an extended mixing chamber, a passage leading from the combustion chamber to the mixing chamber, a screen disposed in the mixing chamber over the outlet of said passage, a controlled inlet and outlet for the mixing chamber, and a suction device 25 connected to said outlet.

8. An apparatus for supplying a drying medium comprising an extended combustion chamber, an extended mixing chamber hav-

ing a controlled air inlet at one end and an outlet at the other end, a passage leading from said combustion chamber into said mixing chamber between said inlet and outlet, a screen removably disposed in the mixing chamber over the outlet of said passage, and means connected to the outlet of the 35 mixing chamber for exhausting, additionally mixing and conducting away the combustion products and air.

9. An apparatus for supplying a drying medium comprising a combustion chamber, means for maintaining combustion therein under reduced pressure and for conducting away the combustion products, controllable means for admitting air to the combustion products, and means for at will changing 40 the direction of flow of said combustion products.

10. An apparatus for supplying a drying medium comprising a combustion chamber, means for maintaining combustion therein under reduced pressure and for conducting away the combustion products, and controllable means for at will admitting air to the combustion products or diverting the combustion products through said air admission means.

Signed at New York, in the county of New York and State of New York, this 28 day of March, 1922.

CHARLES E. BRADLEY.
JOSEPH G. COFFIN.
